(57) **CLAIM**

The ornamental design for a vehicle rear decklid, as shown and described.

DESCRIPTION

FIG. 1 is a top, front and side perspective view and of a vehicle rear decklid showing our new design;

FIG. 2 is a front view thereof.

FIG. 3 is a top, front and opposite side perspective view thereof;

FIG. 4 is a side elevational view thereof;

FIG. 5 is a bottom plan view thereof; and,

FIG. 6 is an opposite side elevational view thereof.

It will be understood that the broken lines shown in the drawings illustrate portions of the vehicle rear decklid that form no part of claimed design.
